METHOD OF REFINING PETROLEUM OIL DISTILLATES

John D. Fields, Los Angeles, Calif.

Application March 18, 1933, Serial No. 661,471

9 Claims. (Cl. 196—23)

My invention relates to a method of refining distillates and more particularly pertains to a process for treating petroleum distillates to remove certain impurities therefrom in which a catalytic action of an alkali metal is employed in a manner similar to and for the purposes set forth in United States Letters Patent Number 1,864,719, issued to me under date of June 28, 1932, for "Method of refining distillates".

10 An object of the invention is to provide a method of the above character whereby the purification of distillates to effect the production of a sweet smelling, water white, stable product of great brilliancy, may be obtained by removing undesirable substances or compounds contained in the distillate which impart to it objectionable odors and discoloration, and which render it unstable, through the medium of an alkali metal catalyst, in which the treatment of the distillates may be effected in a closed tank with either a continuous or intermittent operation, without the use of mechanical agitators, pumps or like instrumentalities, and whereby the purifying treatment may be effected at atmospheric temperatures and pressures and in such manner as to accomplish the refining and purification of the distillates at greatly reduced cost over processes now generally in use.

Another object is to provide a method of purifying distillates with the aid of alkali metal catalysts in which the impurities will separate from the liquid under treatment in a tank in such manner that the impurities may be readily removed from the refined product, and in which the impurities are rendered of such character as to have commercial value.

Another object is to provide a process of the above character in which the purification action may be rapidly effected and without appreciable loss of light gasoline vapors and without loss of the octane number or other aromatics and thus avoid raising the boiling point of the resultant gasoline.

Another object is to provide a distillate refining method in which the distillates are acted on by an alkali metal catalyst in such manner as to effect coagulation and precipitation of gums in the liquid under treatment, and in which dissolving of such coagulated substances held in suspension in the liquid together with the gums that have been precipitated on the alkali metal catalysts will be effected to form a heavy oil which may be readily drawn off from the liquid under treatment.

55 Another object is to provide a process which is

applicable for use in the purifying of pressure distillates either before or subsequent to treatment by the usual acid process, or independent thereof, and which where employed subsequent to the acid treatment the use of sodium plumbite 60 will be obviated.

A further object is to provide a distillate refining process employing an alkali metal catalyst in which the amount of consumption of alkali metal required for treatment of a particular quality of distillate may be accurately predetermined.

The invention and the mode of accomplishing the objects and advantages above set forth, together with such other objects and advantages as may subsequently appear, further resides in the 70 steps and features hereinafter more fully described and claimed and illustrated by way of example in the accompanying drawing in which the figure is a diagrammatic view of a distillate refining apparatus and depicting the manner of carrying 75 the invention into effect.

The apparatus as shown in the drawing embodies a tank 2 for containing the distillates during treatment and which tank for the purpose of facilitating a substantially uniform action 80 throughout the liquid body therein is formed with a downwardly converging or conical shaped bottom portion 3 from the lower end of which leads a discharge pipe 4 fitted with a cut-off valve 5.

The upper end of the tank 2 is provided with an 85 opening 6 fitted with a cover 7 and which opening is provided for the purpose of giving access to the interior of the tank and for enabling the insertion into the tank and removal therefrom of a cage 8 carrying catalytic bodies 9 which bodies 90 are formed of solid alkali metal such as sodium, potassium, or lithium. The cage 8 may be of any suitable construction, being here shown as formed of wire netting but manifestly may be of any suitable open formation to permit circulation of 95 liquid therethrough. One end of the cage is fitted with a removable cover 10. A rack 12 is provided at a suitable point within the tank for affording a support for the cage 8.

In some instances cage 8 may be dispensed with 100 and the alkali metal bodies placed loose in the tank 2.

The distillates to be treated are delivered to the tank from any suitable source of supply through a conduit 14 fitted with a valve 15 which 105 conduit leads into the upper portion of the tank. As a means for conveying gases from the tank so as to prevent development of excessive pressures therein, the upper end of the tank is fitted with a vent pipe 16 equipped with a cut-off valve 17. 110

An important feature of the present invention resides in delivering to the distillate content of the tank a halogen salt in solution, and for this purpose a reservoir is provided for such solution, 5 as indicated at 18, from which leads a conduit 19 communicating with the upper end of the tank through a regulating valve 20. The reservoir 18 is fitted with a suitable measuring gage 21 to enable drawing off of a predetermined volume of 10 the solution from the reservoir 18.

The tank 2 is equipped with a gage glass 22 for indicating the level of the distillates within the tank, and is also fitted with a gage glass 23 for indicating the level of a heavy oil embodying 15 separated impurities which accumulate in the lower portion of the tank.

While the present method is applicable to the treatment of petroleum distillates of various fractions or combinations thereof, it is especially applicable to the treatment of distillates of low boiling point, that is distillates which pass off at temperatures up to approximately 500 degrees Fahrenheit, and may be distillates derived from heavy petroleum oils by cracking. In fact the method 20 is designed to be employed in the treatment of any hydrocarbons containing impurities which are subject to being removed as herein set forth by the action of alkali metal catalysts.

As an example of impurities that are subject 30 to being removed by this process are those of resinous and gummy character and include the olefin hydrocarbons embracing mono-olefins, the di-olefins or poly-olefins, and the acetylene isomers of di-olefins; naphthenes; sulfur compounds; nitrogen bases and acid compounds.

Without binding myself to any particular theory 40 of operation it seems proper to state that the impurities removed or to be removed are such that cold solid alkali metal may act as a catalyst to produce a condensing reaction to form products which are soluble in a menstruum embodying halogen salts, these products being usually of a gummy or resinous or rubbery nature which coagulate, and which undoubtedly include certain 45 sulfur compounds and which when present in distillates impart an objectionable odor and discoloration thereto and which render the distillates unstable and also result in the formation of gums or resinous deposits on utilizing the refined product as in combusting it in motors.

The alkali metal catalyst is employed in the 50 form of solid bodies which are so shaped that they may be arranged within the cage 8 in a manner to afford interstices through which the distillates may flow and in such manner as to cause the flowing distillates to be deflected into numerous small streams between adjacent catalytic bodies, and whereby the distillates will be brought into superficial contact with or in close 55 proximity to a considerable area of the surface of the catalytic bodies. For this purpose the catalysts may be shaped in the form of spheres, blocks or bars. They are placed within the cage 8 through the opening in the upper end thereof, and the cage is placed within the tank through 60 the opening 6 as before described. The catalyst bodies are preferably thus confined in a cage to prevent their floating to the top of the liquid under treatment and also to facilitate the removal and replacement of the catalysts as occasion requires.

The halogen salt solution, which as before 65 stated includes solutions of magnesium chloride, ferrous chloride, zinc chloride, and hydrous aluminum chloride, is prepared in the proportion of

approximately one gram of the halogen salt to one liter of water, but which proportion is subject to variations, the proportions being such that the solution will act as a solvent in cleaning the (resinous and other gummy) impurities from the alkali metal and also to dissolve the coagulated substances held in suspension in the distillates. In other words, the solution may comprise approximately one part in 100 of halogen salts to 99 parts of water by weight, thus forming a one per cent solution, but a stronger or weaker solution may be used.

The halogen salt solution may be employed in the proportion of approximately 10 c. c. of the solution to four liters of the distillates, which is equivalent to approximately 10 gallons of solution to one hundred barrels of distillate, but the proportions may be varied since an excess of salt solution is not detrimental.

In carrying the method into effect a quantity 95 of the alkali metal catalysts is placed within the tank, as in the cage 8; which quantity is proportioned to the volume of distillates to be treated, and according to the proportions of impurities contained in the distillates to be treated, for example if tests show that the distillates to be treated carry approximately 250 milligrams of gum per 100 c. c. of distillates, then approximately two and one-half ounces of alkali metal will be employed for each forty-two gallon barrel of distillates to be treated. In other words, assuming the tank to be of 100 barrel capacity, then the quantity of alkali metal used will be approximately 250 ounces. It will be understood, however, that the proportions may be varied as occasion 100 requires. Manifestly an excess of the alkali metal in proportion to the volume of distillate under treatment will not be detrimental.

A predetermined volume of distillates to be treated is then delivered to the tank and confined therein; the valves 5 and 15 then being closed. A precipitation of heavy gums immediately commences due to the catalytic action of the alkali metal; which effects condensation of such impurities into a flocculent form. The flocculent impurities whose coagulation has thus been effected by the action of the catalysts collect in part on the catalyst bodies, and a portion of such impurities are suspended in the distillates. This action of the alkali metal is immediate and 105 on such action having occurred a measured volume of the halogen salt solution in the proportion above stated is delivered to the tank, as by opening the valve 20, which solution on flowing into the distillates within the tank sinks therein and 110 comes in contact with the alkali metal thereby immediately effecting the evolution of hydrogen gas and thus causing violent agitation of the liquid in the tank.

This agitation serves to cause all of the liquid 115 in the tank to be brought into intimate contact or close association with the alkali metal and thereby causing the latter to effect formation of the flocculated or coagulated impurities throughout the liquid under treatment and also causing 120 the salt solution to act on such impurities as are held in suspension in the distillates and also deposited on the alkali metal catalysts; the salt solution acting as a solvent to convert the coagulated substances (resins and gums) into a heavy 125 reddish oil which settles to the bottom of the tank from whence the oil may be drawn off as by opening the valve 5 from time to time as occasion may require or on completion of the treatment of the charge.

5 The process above described is carried out at normal atmospheric temperatures or at the ordinary temperatures of the liquid distillates, and does not require the generation and application of extraneous heat. The process is also carried on at normal atmospheric pressures; the evolved gases which may accumulate in the tank and thereby create pressures therein being drawn off as occasion requires through the vent pipe 16.

10 By this process no mechanical agitation of the liquid is necessary since the agitation set up from the formation of hydrogen gas effects the requisite contact of the distillates with the alkali metal and also the intermixture of the salt solution and the distillates, within a short period. It has been found in practice that approximately 10 minutes is required to effect treatment of a batch of distillates in the manner above set forth where the proper proportions of distillate, alkali metal and 15 salt solution are employed.

15 The resultant red oil which contains the removed impurities in solution constitutes a saturated solution of sodium hydroxide which is readily separable from the distillates and is a product of commercial value.

20 The resultant distillates will be practically free of objectionable gum and sulfur compounds and is fit for use for commercial purposes, and if redistilled the majority of distillates will be water 25 white and will be stable when exposed to sun light.

25 However there are instances where because of the nature and quantity of resinous, gummy and sulfur compound impurities contained in some distillates, it is found desirable to employ the present process in conjunction with the sulfuric acid process either preliminary or subsequent thereto, in which instance it is found that a much lesser quantity of sulfuric acid is required for carrying out the acid treatment than where such acid treatment is employed alone, and also that it is unnecessary to employ the usual doctor treatment with sodium plumbite as ordinarily used in the acid process. Where the present process is to be employed together with the acid process 40 the distillates are treated with a solution of one to three lbs. of 60 Baumé sulfuric acid per barrel of distillates under treatment. As before stated this acid treatment may be effected either before or after treatment by the present process.

50 The process is highly economical since it has been found in practice that in the treatment of a cracked or pressure distillate containing approximately 250 milligrams of gum per 100 c. c. only about 2½ grams of alkali metal will be consumed per gallon of distillates treated, or in other words approximately two and one-half ounces per barrel.

55 While I have shown and described a particular apparatus for carrying the invention into effect, various other structures may be employed. In fact the invention may be practiced by means of the ordinary distillate storage tanks, and without the provision of any special equipment. Furthermore while the mode of operation has been described as intermittent, that is to say, as applied to the treatment of a batch of distillates in a tank which after being treated is drawn from the tank and the latter recharged, it is manifest that the method may be carried out by a continuous operation, as by maintaining a flow of distillates and salt solution in proper proportions over a mass of alkali metal catalysts.

60 I claim:

65 1. The method of removing impurities from petroleum distillates, consisting in subjecting a

70 relatively large volume of such distillates in liquid condition to the catalytic action of a relatively small mass of solid bodies of an alkali metal in the cold, for a sufficient period of time to effect coagulation of the bulk of the impurities, whereby some of the impurities become precipitated on the alkali metal and some is held in suspension in the distillates in a flocculent state, then adding to the distillates a relatively small quantity of a solution of halogen salts whereby the coagulated impurities will be dissolved and converted into a heavy oil and separating said oil from the distillates.

75 2. The method of removing from petroleum distillates impurities contained in solution therein, consisting in maintaining a relatively small mass of solid bodies of alkali metal and a relatively large volume of the distillates in intimate juxtaposition while at about normal atmospheric temperature, for such length of time as to effect coagulation of at least a major portion of the impurities in the distillates treated, then adding to the distillates a small volume of a solution of mineral salts capable of dissolving the coagulated impurities and to convert same 80 into a heavy oil and separating said oil from the distillates.

85 3. A process which comprises placing a relatively small mass of solid alkali metal within a large bulk of petroleum oil distillates, to cause 90 coagulation of certain substances in said distillates, introducing into the distillates and into contact with said alkali metals a small volume of a solution of halogen salts to effect evolution of hydrogen gas and resultant agitation of the 95 distillates and to cause said solution to dissolve the coagulates into a heavy oil, and separating said oil from the distillates.

100 4. A process which comprises placing a relatively small mass of solid alkali metal within a relatively large bulk of petroleum oil distillates and maintaining said metal within the distillates until coagulation of substances in the distillates takes place, then contacting the alkali metal while in the distillates with a small 105 volume of a halogen salt solution to effect evolution of hydrogen gas, and supplying such volume of said salt solution to the distillates as to effect conversion of the coagulates into oil, and removing the oil and formed gases.

110 5. A process which comprises placing a relatively small mass of solid alkali metal within a relatively large bulk of petroleum oil distillates and maintaining said metal within the distillates until coagulation of substances in the distillates 115 takes place, then contacting the alkali metal while in the distillates with a small volume of a halogen salt solution to effect evolution of hydrogen gas, and supplying such volume of said salt solution to the distillates as to effect conversion of the coagulates into oil, removing the oil and formed gases, subjecting the remaining 120 distillates to the action of sulfuric acid, and finally washing and redistilling the distillate product.

125 6. The process of refining petroleum oil distillates which consists in placing within a relatively large bulk of distillates a relatively small mass of solid alkali metal, adding to the distillates a small volume of a halogen salt solution 130 of about one per cent strength in such manner as to bring said solution and alkali metal into contact, employing said solution in such proportions as to effect dissolution of at least a portion of said alkali metal and to effect dissolv-

ing of coagulates formed in the distillates by the catalytic action of the alkali metal.

7. In a process for refining petroleum oil distillates, the step which consists in adding a small volume of a solution of halogen salts to a large bulk of distillates containing a relatively small amount of solid alkali metal.

8. The process of refining petroleum oil distillates to effect removal of resinous and gummy constituents thereof consisting in subjecting the distillates to the combined action of a solid alkali metal and a solution of halogen salts in substantially the proportions of ten gallons of the salt solution and two hundred and fifty ounces

15

of alkali metal to one hundred barrels of distillates.

9. The process of refining petroleum oil distillates to effect removal of resinous and gummy constituents thereof consisting in subjecting the distillates to the combined action of a solid alkali metal and a solution of halogen salts in substantially the proportions of ten gallons of the salt solution and two hundred and fifty ounces of alkali metal to one hundred barrels of distillates at substantially normal atmospheric temperatures.
